UNITED STATES PATENT OFFICE.

JOHN ERICKSON, OF CHICAGO, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

Application filed May 25, 1922. Serial No. 563,477.

To all whom it may concern:

Be it known that I, JOHN ERICKSON, a citizen of the United States of America, and a resident of Chicago, Cook County, and 5 State of Illinois, have invented certain new and useful Improvements in Measured-Service Telephone Systems, of which the following is a specification.

The present invention relates to measured service telephone systems in general, but is particularly concerned with measured service equipment for automatic telephone systems. More specifically, the invention provides an improved time controlled substation 15 meter for use in systems of the above character, and having a number of novel and useful features which will be pointed out and described hereinafter, reference being had to the accompanying drawing.

20 In the drawing, an automatic substation A of the usual type is shown equipped with the improved substation meter M. The substation A' is identical with the substation A and is equipped with the meter M' which is 25 similar to the meter M, and which is denoted by the rectangle bearing the reference character M'.

The line switch C in which the line of substation A terminates, the selector D 30 which is accessible to the line switch C, the selector E which is accessible to the selector D, which switches are denoted by the dotted rectangles bearing those reference characters, and the final connector F may be automatic switches of any desired or well known 35 type, except that the connector F is required to be of the particular type in which the incoming trunk conductors are reversed when the called subscriber answers. The 40 line and back bridge relays only of the connector F, or the ones which are needed to explain the operation of the improved meter M, are shown.

The improved meter M comprises a polarized relay 3, operating magnet 6 and associated armature 7, meter wheel 14, and the train of clock-wheels and escapement controlled by armature 7; together with the latch 8 and associated spring contacts.

50 In order to describe the operation of the meter M, it will be assumed that the subscriber at substation A desires to converse with the subscriber at substation A'. When the receiver is removed at substation A, the line switch C operates in the well known

manner to extend the line of substation A to an idle first selector, the first selector D for example. The current flow over the line of substation A passes through the receiver, the transmitter, the impulse spring 60 of the calling device CD, spring 4 of polarized relay 3 and its resting contact, and polarized relay 3. Polarized relay 3 energizes at this time, but in a direction opposite to that in which it must energize in order to 65 operate spring 4.

The calling subscriber now operates his calling device in accordance with the digits in the desired number, whereupon the first selector D, and a second selector, the selector E for example, and a connector, the connector F for example, are operated in the usual manner to extend the connection to the line of substation A'. The connector F now applies ringing current to the called 75 line in the well known manner to ring the bridged bell at the called substation.

When the called subscriber responds by removing his receiver, the source of ringing current is removed from the called line and the wipers of the connector F are connected up, as shown by the dotted conductors. When this occurs, back bridge relay 20 energizes over the called subscriber's line and reverses the line conductors incoming to the 80 connector F as regards their connection with the windings of line relay 21, thereby reversing the direction of current flow in the calling line. When this occurs polarized relay 3 is energized in the opposite direction and 85 operates spring 4, thereby removing the shunt from around magnet 6. Magnet 6, upon energizing, attracts armature 7, whereupon the pawl 13 draws the number wheel 14 forward to register the call, and the pawl 90 12 is advanced past two teeth on the associated ratchet wheel. Just before armature 7 comes into engagement with its front stop 10, the end of armature 7 comes into engagement with spring 15 and pushes it beyond 100 the end of the locking lever 8, whereupon spring 5 comes into engagement with its associated contact and the locking lever drops behind spring 15 and locks it in its operated position.

When spring 5 comes 105 into engagement with its associated contact, it places a shunt around the polarized relay 3, whereupon the said relay 3 deenergizes. Upon deenergizing, polarized relay 3 allows spring 4 to come into engagement with its 110

associated contact, thereby short circuiting magnet 6. When this occurs magnet 6 de-energizes and armature 7 starts back to normal, being operated by the spring 16. In order for armature 7 to return to normal, the first clock wheel must be advanced the distance represented by two teeth on the associated ratchet wheel and the other clock wheels of course, move a greater distance. The escapement now begins to operate in the usual manner and the clock wheels slowly move and allow armature 7 to be retracted slowly. The time required for armature 7 to be fully retracted may be varied to suit different requirements.

The subscribers, of course, may begin to converse with each other upon the removal of the receiver at the called substation and, in case the conversation is terminated before armature 7 reaches its normal position, no further charge is made. Assuming, however, that the conversation is extended beyond the predetermined limit, the initial charge is repeated when the armature 7 reaches its normal position, as will now be described. Just as armature 7 reaches normal position shown in the drawing, the end thereof strikes the knob 9, thereby forcing the lever 8 up out of engagement with spring 15. The springs 15 and 5 now return to normal position and the latter removes the shunt from around polarized relay 3, whereupon the said relay 3 energizes and operates spring 4. Spring 4, upon being operated, removes the shunt from around magnet 6, whereupon the above described operation is repeated. The meter M repeats this cycle of operation over and over until the conversation is completed.

When the conversation is completed the two subscribers replace their receivers. When the receiver is replaced at the called substation, the circuit of back bridge relay 20 is opened. The said relay 20, upon deenergizing, reverses the current flow in the calling line to normal. When the receiver is replaced at the calling substation the circuit of line relay 21 of the connector F is opened, whereupon the connection is released in the usual manner.

It will be noted that the current flow in the called line is in the same direction as the current flow in the calling line before the called subscriber has answered. Consequently, the called subscriber's meter is not operated.

The various features of the invention, having been described and ascertained in the foregoing, will be pointed out in the appended claims.

What is claimed is:

1. In a telephone system, a calling line, another line, a substation on said calling line, a charge assessing device at said substation comprising a relay, a magnet, a timing de-

vice, and a register, means for extending a connection from said calling line to said other line, means responsive to the answering of the subscriber on said other line for operating said relay by causing a current change in said calling line, means controlled by said relay for energizing said magnet, means responsive to the energization of said magnet for operating said register and for restoring said relay, means controlled by the restoration of said relay for starting said timing device by deenergizing said magnet, and means controlled by said timing device for again repeating the initial operation of said relay.

2. In a telephone system, a calling line, a substation on said line, a meter at said substation, another line, means for extending a connection from the first named line to said other line and for signalling a subscriber thereon, means controlled by the response of the subscriber on said other line for actuating said meter to register a completed connection by reversing the current flow in the calling line, means including a timing device associated with said meter for repeatedly actuating said meter at predetermined intervals during the conversation, and a magnet energized over a talking conductor of the calling line by current supplied from the exchange for supplying power to operate said timing device and said meter, and circuits for supplying current to the magnet as set forth.

3. In a telephone system, a line, a substation on said line, a meter associated with said substation, a second line, means for extending a connection from the first mentioned line to said second line and for signalling a subscriber thereon, a magnet controlled over a talking conductor of said first line by the response of the subscriber on said second line for operating said meter, a timing device individual to said meter, and means controlled by said timing device and said magnet for repeating the operation of said meter at intervals.

4. In a substation meter, a vibratory device comprising a relay and a magnet adapted to be energized over the line circuit, the relay having an armature controlling the magnet circuit and the magnet having an armature controlling the relay circuit, a counting device actuated by the magnet armature, and a clock train for controlling the rate at which the magnet armature is operated.

5. In a substation meter, a vibratory device comprising a relay and a magnet adapted for energization over the line circuit, the said magnet being normally short circuited, an armature for the relay for removing the short circuit around said magnet, an armature for the magnet adapted to place a short circuit around said relay, a counting device

and means for advancing it every time said magnet armature is operated, and a timing mechanism for regulating the rate at which said magnet armature is operated.

5. 6. In a substation meter, a spring driven clock train, a winding magnet for tensioning the driving spring, a counting device for counting the number of times said winding magnet is operated, and a circuit including 10 the talking conductors of the subscriber's line for operating said winding magnet.

7. In a substation meter, a spring driven clock train, a winding magnet for tensioning the driving spring, a counting device for 15 counting the number of times said winding magnet is operated, a circuit including the talking conductors of the subscriber's line for operating said winding magnet, a polar relay associated with said winding magnet, 20 and contacts so connected that the relay and magnet exercise a reciprocal control over each other whereby the magnet is operated intermittently.

8. In a telephone system, a calling line, 25 means for completing talking connections from said line to called lines, a substation

for said line equipped with a meter, and an electromagnetically driven timing device also at the substation for causing said meter to operate at definite intervals over the talking conductors of the calling line during a talking connection.

9. In a telephone system, a subscriber's substation, charging means including a relay, 30 automatic means for causing the actuation of said relay, a timing device, and means associated with said relay for rendering said timing device effective to render said automatic means ineffective for a definite period, said automatic means thereafter 40 again rendering said charging means effective to operate the meter.

10. In a telephone substation set, a timing device, a call metering device, joint means for operating said devices, and a relay associated with the timing device and controlled thereby for rendering the metering device effective to repeat the registering operation after a definite interval.

In witness whereof, I hereunto subscribe 50 my name this 19th day of May, A. D., 1922.

JOHN ERICKSON.
